ARC EXTINGUISHER

James M. Wallace, Pittsburgh, and Howard W. Graybill, Greensburg, Pa., assignors to Westinghouse Electric Corporation, East Pittsburgh, Pa., a corporation of Pennsylvania

Application May 31, 1951, Serial No. 229,090

3 Claims. (Cl. 200—149)

1

This invention relates to circuit interrupters and more specifically to circuit interrupting devices embodying arc confining and extinguishing members comprising nylon.

Arc extinguishing materials are applied in or adjacent to those portions of circuit interrupters that are subject to the establishment of an arc when in service. The heat of the arc will effect a decomposition of the arc extinguishing material resulting in an evolution of large quantities of gas which destroys or extinguishes the arc, or creates a condition whereby the arc cannot be sustained. In addition to the gas evolving qualities of the arc extinguishing material, it must also be and remain an insulator at all times, and substantial quantities of conducting carbonaceous material, such as soot, should not be formed on the surface of the arc extinguishing material as a result of having been subjected to an arc.

A material frequently used as an arc extinguishing material is boric acid. However, the use of boric acid has been unsatisfactory in many cases because of its relatively low mechanical strength and other physical properties. In particular, boric acid is difficult to form or shape by molding, with or without machining. Thus, the lack of suitable mechanical properties make it difficult to use boric acid in many applications for which its electrical arc extinguishing characteristics are otherwise satisfactory. The same limitations apply to numerous other inorganic solids which when subjected to arcing conditions will give off a gas. For instance, magnesium borate, oxalic acid, ammonium borate and the like by themselves are weak mechanically, thus placing a limitation on their use as an arc extinguishing material.

It is also to be noted that fiber may be employed in circuit interrupters with some success since it possesses a high degree of mechanical strength, in spite of the fact that its arc interrupting ability is not quite as satisfactory as that of boric acid. However, fiber is subject to warping whereby satisfactory operation of circuit interrupters employing the fiber may be detrimentally affected.

An object of this invention is the provision of a circuit interrupter having an arc confining and interrupting structure comprising nylon.

A further object of this invention is the provision of an arc confining and interrupting structure suitable for repeated use comprising a nylon material which evolves an adequate amount of gas for extinguishing an arc and has a low rate of erosion or deterioration.

These and other objects of this invention will become apparent upon consideration of the following description and the attached drawings, in which:

Figure 1 is a cross-section through one form of circuit interrupter;

2

Fig. 2 is a cross section through an elevation view of a fuse link;

Fig. 3 is a view partly in plan and partly in section of the device shown in Fig. 4, the section being indicated by the line III—III thereof;

Fig. 4 is an elevation view of a disconnect switch;

Fig. 5 is a graph plotting loss by erosion against amperes and showing the erosion of numerous arc extinguishing materials for various current inputs to a circuit interrupter; and

Fig. 6 is a graph plotting restored kilovolts on an arithmetic scale against amperes on a logarithmic scale and illustrating the interrupting characteristics for a plurality of fuses each having an arc extinguishing member comprising a different material.

According to the present invention, arc confining and extinguishing portions of circuit interrupters are prepared from nylon or superpolyamides, which we have found have unusually low erosion characteristics when repeatedly subjected to an arc.

There are a plurality of processes for producing nylon or superpolyamide resin and the following described process is only one of many such processes. In this process polyamides are obtained from polyamide-forming reactants, as for instance by self-polymerization of aminocarboxylic acids or by heating a polyamine with a polycarboxylic acid under polymerizing conditions until a high molecular weight polyamide is obtained. Particularly useful for the present purpose are the linear or fiber-forming polyamides or superpolyamides disclosed in U. S. Patents 2,071,253 and 2,130,948. However, non-fiber forming superpolyamides may be employed. The reaction of unsaturated polycarboxylic acids such as malic acid with or without a saturated dibasic acid, with a polyamine will produce cross-linked superpolyamide resins. The linear polyamides, which are usually definitely crystalline rather than resinous, are obtainable from bifunctional reactants, as for instance from diamines and dicarboxylic acids or by the self-polymerization of monoamino monocarboxylic acids or their amide-forming derivatives, e. g., the lactams, the reaction being continued until the polyamide has a viscosity of at least 200 poises at 285° C. or has an intrinsic viscosity of 0.6 as defined in U. S. Patent 2,130,948. These nylon polymers as defined herein include, but are not limited to, the linear fiber-forming polyamides which contain recurring amide groups as an integral part of the main chain of atoms in the molecule and which are obtained by including with the polyamide-forming reactants other bifunctional reactants, such as glycols in which case esteramide interpolymers are obtained.

Although the larger portion of the arc extinguishing member should comprise nylon, it is

to be understood that for securing excellent results, both mechanically and electrically, the arc extinguishing material may contain other substances. Less than 50% of the weight of the arc extinguishing member may be composed of reinforcing fibers, such as asbestos or glass fibers, or solid, inorganic materials, such as titanium dioxide, silica, magnesium oxide, or the like. It will be appreciated that other gas evolving materials, such as boric acid, ammonium borate or magnesium borate, as well as reinforcing solids, may be incorporated in the nylon.

Referring to Fig. 1 of the drawings, there is illustrated a circuit interrupter comprising a stationary contact member 10 having a passage 12 therein. The stationary contact member 10 is threadedly engaged with a tube or sleeve 14 of nylon which is capable of evolving arc extinguishing gas in the presence of an electrical arc. The remainder of the circuit interrupter comprises a movable contact member 16 which is disposed for reciprocating motion within a passage 18 contained within the tube 14.

In operation, a circuit may be closed by actuating the movable contact member 16 downward into engagement with the stationary contact member 10. On actuating the movable contact member 16 upward from its circuit closing position, an arc will be established between the movable contact member 16 and the stationary contact member 10 which arc will effect a partial decomposition of the nylon forming the tube 14, thus evolving an arc extinguishing gas. The arc extinguishing gas resulting will flow to the passage 12 and will exert a cooling and deionizing effect on the arc, thus extinguishing it.

Referring to Fig. 2 of the drawings, there is illustrated a fusible interrupting device which comprises another embodiment of this invention. The fusible interrupting device comprises an elongated insulating tube 20 of nylon having a terminal ferrule 22 threadedly engaged with the upper end thereof, and a lower terminal collar 24 disposed around the outside of the insulating tube 20 adjacent the lower end thereof and secured in position on the tube by a set screw 26.

In order to secure a removable fuse link unit 28 within the fusible interrupter, an upper terminal cap 32 is threadedly engaged with an extension of the terminal ferrule 22 so that the upper portion 34 of the removable fuse link unit 28 is secured between the cap 32 and the upper portion of the ferrule 22. The fuse link unit 28 comprises an upper terminal portion 36 electrically connected by a fusible member 38 to a lower terminal strip 40, all of which are disposed within a relatively small arc confining and extinguishing tube 42 of nylon. The lower terminal strip 40 is resiliently held away from the upper terminal strip 36 by means of a spring 44 held in compression between the tube 42 and a pin 46 connected to the lower end of the lower terminal strip 40. For the purpose of completing an electrical circuit from the lower terminal strip 40 to the lower terminal collar 24 one end of a flexible conductor 48 is connected by soldering, or the like, to the lower terminal strip 40 and the other end of the conductor 48 is electrically connected to the lower terminal collar 24 and there held in place by the set screw 26.

The main function of the tube 42 is to confine low current arcs resulting from the fusion of the fusible member 38 so that the nylon gas evolving composition comprising the tube is in close prox-

imity to the fusible link unit 28, thereby assuring a rapid and efficient extinction of arcs of low current value. When the fusion of the member 38 is due to a short circuit which effects a high current flow through the circuit interrupter, the tube 42 is sufficiently weak to completely disintegrate, thereby relieving the gas pressure developed and permitting the arc extinguishing gases to expand within the larger volume encompassed by the tube 20 as well as permitting the arc to come in contact with the tube 20, thus developing sufficient gas to assure the extinction of the arc. For this reason the tube 42 is preferably composed or prepared from a composition having somewhat more fibrous reinforcement than the tube 20, for example, 10% or more by weight of fibrous material.

Referring to Fig. 4 of the drawings, there is illustrated still another embodiment of the teachings of this invention. The disconnect switch 20 illustrated comprises a pair of supporting insulators 50 and 52, such as porcelain insulators or the like, on which the switch proper is mounted. The supporting insulator 52 is illustrated as having a hinge tongue casting 54 secured thereon as by bolts 56, and it is provided with an integral terminal 58 to which a line conductor may be secured in any desired manner. The hinge tongue casting 54 is apertured for the reception of a pivot bolt 60 for pivotally mounting a split switch blade 62.

The supporting insulator 50 is adapted to support a stationary contact tongue 64 having an integral base which is secured to the insulator 50 and having an integral outwardly extending terminal 66 to which a line conductor may be secured in any desired manner. The stationary contact tongue 64 is preferably provided with a slot for receiving bolt 68 in the closed position 40 of the switch, as illustrated in Fig. 4. An actuating handle 70 is adapted to be secured between the outer edges of the sides of the blade 62 and is preferably provided with a hookeye 72 for the reception of a hookstick, operating member or the like.

For the purpose of interrupting load currents, switch blade 62 is provided with an auxiliary snap acting blade 74 adapted to be disposed in spaced relation with respect to one side of the blade 62. The auxiliary blade 74 is mounted by means of bolts 75 on a box-like casting 76 which is supported in turn by a pivot bolt 82 so as to be freely rotatable on this bolt, which is secured in the split blade 62. The side of the mounting casting 76 which lies adjacent the main blade 62 is notched, as shown at 88, to receive a stop screw 90 mounted in the main blade 62. The purpose of stop screw 90 is to limit pivotal movement of the auxiliary blade 74 relative to the main blade 62.

The structure thus far described is substantially identical to that structure disclosed in the Rawlins Patent No. 2,308,026, and accordingly for a more complete description of such parts and their operation, reference may be made thereto.

However, this invention is primarily concerned with the material from which arc chute 94 is constructed. The arc chute 94 comprises a pair of spaced plates 96 which may be machined or molded to shape. The plates 96 are provided with liners 98 and 100 which are disposed adjacent the spring-biased contact clips 91 and the cooperating snap acting blade 74. The liners 98 and 100 are formed from nylon and they are

maintained in place by means of the screws 102. It is of course to be understood that the plates 96 and the liners 98 and 100 could be integral.

When it is desired to open the switch from the closed position, as shown in Fig. 4, a hook-stick or other operating member is inserted in hookeye 72, and the main blade 62 is pulled away from the stationary contact tongue 64. However, the auxiliary blade 74 is held frictionally between the spring-biased contact clips 91, while the auxiliary blade 74 rotates on the pivot bolt 82 and stresses a spring 92. This movement of the parts continues until the main switch blade 62 is separated a substantial distance from the stationary contact tongue 64, and the other side of notch 88 of the mounting fixture 76 engages the stop screw 90 whereupon continued opening movement of the main switch blade 62 causes the auxiliary plate 74 to be pulled out of the spring-biased contact clips 91. As soon as the auxiliary blade 74 escapes from frictional engagement with the clips 91, its biasing spring 92 acts to rapidly move the auxiliary blade counterclockwise relative to the main blade 62 in a pivotal manner about the bolt 82 to restore it to a parallel relationship with the main switch blade 62, this movement being arrested by the engagement of the side of the notch with the stop screw 90. Preferably, this snap action of the auxiliary blade 74 takes place substantially throughout the narrow slot formed between the liners 98 and 100 of nylon so that the arc drawn upon separation of the auxiliary blade 74 from the spring-biased contact clips 91 will be very rapidly elongated through the arc chute 94 and extinguished therein. The liners 98 and 100 of nylon composition when subjected to such an arc will develop a large quantity of un-ionized arc cooling gases and the use of nylon assures a rapid and effective extinction of the arc as well as other advantages which will be herein-after mentioned.

In order to return the disconnect switch to the circuit closing position, the main switch blade 62 is manually actuated into engagement with the stationary contact tongue 64. During the closing movement of the main blade 62 the auxiliary blade 74 remains parallel thereto due to the combined action of the stop screw 90 and the notch 88 in the fixture 76.

Referring to Fig. 5, there is illustrated a graph which represents the erosion characteristics for fuse members whose arc extinguishing material are made from fiber, boric acid and nylon, respectively. These tests were conducted with separate groups of 4 inch fuses having a $\frac{1}{4}$ inch bore, a group being made from fiber, boric acid and nylon, respectively. It is to be noted that, as indicated by these tests, the loss in grams per half cycle of arcing for any one of the various values of current flow through the fuse constructed of nylon was only a small percentage of that loss indicated for the fuses constructed of fiber or boric acid. Thus, by manufacturing the arc extinguishing material utilized on various circuit interrupters from nylon, the operating life of the circuit interrupter can be greatly extended, which is an extremely important factor.

Referring to Fig. 6, there is illustrated a graph which represents the interruption characteristics for fuse members having arc extinguishing members made from boric acid, fiber, and nylon, respectively, and whose length and bore are 4

inches and $\frac{1}{4}$ inch, respectively. In particular, the graph illustrates at what open circuit voltage across the fuse and corresponding current flow through the fuse, each fuse will interrupt a circuit within a period of time of five half cycles of arcing. It is to be noted that the fuse made from nylon has far superior interruption characteristics as compared to the boric acid and fiber fuses up to approximately 200 root-mean-square amperes. The nylon fuse also has interruption characteristics that are superior to those of the fiber fuse up to approximately 400 root-mean-square amperes. The superior interruption characteristics for the nylon fuse permits the use of a smaller size fuse, as compared to the boric acid or fiber fuse, and still have the same interruption characteristics. This is of considerable advantage both from the standpoint of original cost, as well as a saving of space which under many circumstances is extremely important.

Having described preferred embodiments of our invention, we wish it to be understood that the invention is not limited to the particular embodiments disclosed herein since it is apparent that many changes and modifications may be made in the composition and the various structures shown without departing from the broad spirit and scope of the invention.

We claim as our invention:

1. A circuit interrupter comprising in combination a fusible link which may be fused forming an arc, an arc extinguishing and confining means consisting of at least 50% by weight of a resin and the balance being a non-resinous filler, the resin being composed substantially entirely of superpolyamide, the arc extinguishing and confining means being so disposed with respect to the means for establishing an arc as to provide for evolution of an arc extinguishing gas when subjected to the arc.

2. A circuit interrupter including means for establishing an arc, and arc extinguishing and confining means consisting of at least 50% by weight of superpolyamide resin, the balance composed of at least one of the group consisting of fiber reinforcing materials and solid fillers, the arc extinguishing and confining means being so disposed with respect to the means for establishing an arc as to provide for evolution of an arc extinguishing medium when subjected to the arc.

3. A circuit interrupter including means for establishing an arc, an arc extinguishing and confining means consisting entirely of superpolyamide resin, the arc extinguishing and confining means being so disposed with respect to the means for establishing an arc as to provide for evolution of an arc extinguishing medium when subjected to the arc.

JAMES M. WALLACE.
